MERCHANDISE DISPLAY HOLDER

John E. Alexander, Jr., Dearborn, and Robert M. Alexander, Livonia, Mich., assignors to Fre-Bar Inc., Holly, Mich., a corporation of Michigan

Filed Apr. 14, 1964, Ser. No. 79,488

Term of patent 14 years

(Cl. D80—9)

FIG. 3

FIG. 1 is a front elevational view of a merchandise display holder embodying our new design;

FIG. 2 is a side elevational view thereof; and

FIG. 3 is a plan view thereof.

The essential features of our design reside in the portions shown in full lines, it being understood that the broken line representation of bottles in FIGS. 1, 2 and 3 are for purposes of illustration only.

We claim:

The ornamental design for merchandise display holder, as shown and described.
